United States Patent Office.

J. D. SMITH, OF NAUGATUCK, CONNECTICUT.

Letters Patent No. 63,113, dated March 19, 1867.

IMPROVED WINDOW FASTENING.

The Schedule referred to in these Letters Patent and making part of the same.

TO ALL WHOM IT MAY CONCERN:

Be it known that I, J. D. SMITH, of Naugatuck, in the county of New Haven, and State of Connecticut, have invented a new and improved Window Fastening; and I do hereby declare that the following is a full, clear, and exact description thereof, which will enable those skilled in the art to make and use the same, reference being had to the accompanying drawings, forming part of this specification, in which—

Figure 1 is a front view of a window with my improvement applied to its sashes.

Figure 2, a detached side view of my improvement enlarged.

Figure 3, a detached view of the bolt.

Figure 4, a detached view of a metal plug pertaining to the invention.

Similar letters of reference indicate corresponding parts.

This invention relates to an improvement in that class of window fastenings which are composed of a bolt provided with a spiral spring, the bolt working in metallic thimbles fitted in the stile of the sash. The invention consists in an improvement in the thimbles, whereby the same are retained in the stile, being prevented from casually slipping out therefrom, a contingency of frequent occurrence with the ordinary thimbles, and which renders the fastening useless.

A represents a window frame, and B B the sashes, fitted therein in the usual way. C is a slide-bolt, which may be constructed of malleable cast iron, or other metal, having a square or rectangular form, a, at one end, with a shoulder, b, at its inner part, and of round or cylindrical form from the shoulder b to its opposite end, and somewhat curved at said end, as shown at c, (see more particularly fig. 2.) D D' represent the two thimbles, in which the bolt C works. These thimbles are also of metal, and have screw-threads on their exterior. The thimble D is screwed into the outer end of the horizontal hole d, bored in the stile e of the sash, in which the bolt is fitted, said thimble being screwed into said hole, with the bolt C fitted in it; and the other thimble D' is simply driven into said hole, the wood, after the thimble is driven in, filling the thread of the screw, and preventing the thimble from slipping out. To insure this result it will of course be understood that the diameter of thimble D', including the thread of the screw, must exceed a trifle the diameter of the outer end of the hole d in the stile of the sash. The rectangular end a of the bolt catches over shoulder f on metallic plugs E, driven in the sides of the window frame, the spring F, which is placed on the bolt between the two thimbles, having a tendency to throw or keep said end out from the sash.

Having thus described my invention, what I claim as new, and desire to secure by Letters Patent, is—

The combination of the slide-bolt C with the thimbles D D', provided with screw-threads on their exterior surfaces, substantially as and for the purpose herein set forth.

J. D. SMITH.
